(57) **CLAIM**

The ornamental design for the light emitting diode, as shown and described.

DESCRIPTION

FIG. 1 is a perspective view of the light emitting diode in a first embodiment;

FIG. 2 is a front view thereof, a rear view being mirror image thereof;

FIG. 3 is a right side view thereof, a left side view being mirror image thereof;

FIG. 4 is a top plan view thereof;

FIG. 5 is a bottom view thereof;

FIG. 6 is a perspective view of the light emitting diode in a second embodiment;

FIG. 7 is a front view thereof, a rear view being mirror image thereof;

FIG. 8 is a right side view thereof, a left side view being mirror image thereof;

FIG. 9 is a top plan view thereof;

FIG. 10 is a bottom view thereof;

FIG. 11 is a perspective view of the light emitting diode in a third embodiment;

FIG. 12 is a front view thereof, a rear view being mirror image thereof;

FIG. 13 is a right side view thereof, a left side view being mirror image thereof;

FIG. 14 is a top plan view thereof; and,

FIG. 15 is a bottom view thereof.

The portions of the article in broken lines are shown for illustrative purposes only and form no part of the claimed design.
